BEAM TYPE ELECTRON DISCHARGE DEVICE

Paul Georges Chevigny, New York, N. Y., assignor
to Federal Telephone and Radio Corporation,
New York, N. Y., a corporation of Delaware

Application July 8, 1944, Serial No. 544,053

7 Claims. (Cl. 250—27.5)

1

This invention relates to electron discharge devices and particularly those of the beam type.

In electron discharge devices, electrons are normally emitted from the cathode in all directions normal to the surface thereof, but not all this emission serves a useful function. Indeed, emission in certain directions is not only useless but harmful in that it adversely affects the operating characteristics of the electron discharge device.

An object of the present invention is the provision of an electron discharge device having a cathode whose emissive characteristics at various portions of its surface differ in accordance with the requirement of the electron discharge device, for example at certain portions thereof there is substantially no electronic emission.

In beam type electron discharge devices, electronic emission from the cathode in a direction other than along the paths of such beams, serves no useful function, and moreover such unnecessary emission introduces complicating factors adversely affecting the optimum operational characteristics of such devices. Accordingly another object of the present invention is the provision in a beam type electron discharge device having predetermined beam paths between the cathode and anode of a cathode which emits electrons only from those surfaces in the direction of said paths.

Other and further objects and advantages of the present invention will become apparent, and the foregoing will be best understood from the following description of an embodiment thereof, reference being had to the drawing in which:

Fig. 1 is a view, partly in elevation, partly in section, of an electron discharge device embodying my invention;

Fig. 1A is a partial section taken along the line 1A—1A of Fig. 1; and

Fig. 2 is an enlarged metallurgical cross section of one of the filament elements, this view being exaggerated to bring out the details thereof.

Referring now to Fig. 1, numeral 1 generally designates a beam type power tube. The tube envelope 2 includes an upper insulating portion 3 and a lower cylindrical insulating portion 4 joined together by a generally annular member 5 for mounting the grid structure. The member 5 may be of copper and is sealed to the upper and lower portions 3 and 4 of the envelope by any suitable

2

means such as knife edge seals 6. Passing through and sealed in the upper portion 3 of the envelope 2 are the cathode support members 7 and 8 which also serve as current carrying leads.

5 Respectively attached to the inner ends of cathode support members or leads 7 and 8 are metallic rings 9 and 10, each of which in turn has attached thereto a plurality of conducting rods 11 and 12 respectively. Depending from the rods 10 11 and 12 is a cylindrical cathode 13 comprised of a plurality of filament elements 14, each of said filament elements 14 being parallel to the next one and arranged in a circle concentric with the central longitudinal axis of the tube. Filament elements 14 are also spaced an equal distance apart, the lower ends 15 of said elements 14 being bent inwardly and gathered in and attached to a castellated nut 16 which serves to hold the elements in place, and moreover electrically connects the elements together at their lower end. Alternate ones of the elements 14 are connected to rods 11, the rest of said elements 14 being connected to rods 12. It will thus be seen that filament current flows, through leads 7, ring 9, rods 12 and through alternating ones of filament elements 14 which are connected to rods 11 to the castellated nut 16 and then out through the other of said elements 14 which are connected to rods 12, through ring 10 and lead 8.

30 The anode electrode 17 may be formed from a solid block of metal, preferably copper. A suitable knife edge 18 is formed on the outside of the anode structure in order to seal the anode to the lower end of the lower cylindrical portion 4 of the envelope and thus complete the tube envelope. The active portion of the anode or that portion thereof which receives the electron current from the cathode is a cylindrical surface 19 which may be formed by boring a hole in the end of the 35 copper block. The length of this active surface 19 is preferably substantially equal to the length of the cathode facing it. The active surface 19 is concentric with the cylindrical cathode 13. The lower portion 20 of the copper block may be provided with any suitable cooling means (not shown) such as vanes adapted to be cooled by either blasts of air or by circulating liquid medium.

40 Tube 1 also includes two grid electrodes 21 and 22 which are supported from the annular member

5 by means of conical conducting or supporting members 23 and 24, conical members 23 being electrically connected to the annular member 5 and conical member 24 being electrically insulated from said member 5 by suitable washers 25 and connected to a lead-in wire 26 passing through an opening 27 in the annular member 5 and through a pipe 28 which is hermetically sealed by a glass bead 29. Ring 5 serves as the external terminal for grid 21 and lead-out wire 26 serves as the external terminal for grid 22. The aforescribed grid structure and leads are more fully described in my joint copending application for "Electron discharge devices," filed June 26, 1944, Serial No. 542,076, now U. S. Patent Number 2,438,899.

Grids 21 and 22 each consist of a plurality of parallel bars 30 and 31 arranged in circles concentric with the cylindrical cathode 13 and the active anode surface 19. These bars 30 and 31 are held in place by suitable spacing members 32 and 33 at one end and are sealed at their other ends to their respective conical supporting members 23 and 24.

Referring now to Fig. 1A, it will be seen that each of the bars 30 of grid 21 is radially aligned with its corresponding one of bars 31 of grid 22. This arrangement serves to provide uninterrupted radial paths 34 between each pair of aligned bars extending from the active anode surface 19 to one side of the filament elements 14, each of which elements 14 is facing one of said paths 34 in a direct uninterrupted line with the active surface 19 of the anode.

As set forth hereinabove in the objects of this invention, it is desired that the filament elements 14 should only emit electrons from the surface thereof facing the active surface 19 of the anode along the uninterrupted path. The surface 35 of the filament elements 14 facing the active surface 19 of the anode may be a flat surface as illustrated in Fig. 2 so that electrons emitted normal to said surface would tend to go in a beam along path 34 towards the anode and would not spread out laterally as much as would tend to be the case if said surface 35 were curved. Such a structure results in the filament element having a segmental cross section. While surface 35 of filament element 14 is to emit electrons it is desired that the rest of the surface of filament element 14, which may be a curved surface 36, should not emit substantially any electrons.

According to one way of accomplishing this the filament element 14 which may be of the thoriated tungsten type has its flat surface 35 preferably carburized as indicated at 37 while the curved surface 36 is preferably not carburized and may be covered with a coating 38 of a substance which will inhibit emission such as, for example, one or more of the oxides of zirconium, beryllium and titanium or the nitrides of boron, zirconium, beryllium and titanium. This and other methods of accomplishing the foregoing are more fully described in my co-pending joint application entitled "Electrode for electron discharge device and method of producing the same," filed May 19, 1944, Serial No. 536,332.

As shown in Fig. 1A, it will be seen that when the filament elements 14 are arranged in the tube, their flat surfaces 35 directly face the anodes along beam paths 34. It will further be seen that there will be no emission in any of the other directions either towards the center of the tube or sidewise, tangentially of the cathode structure.

While I have described a single specific embodiment of my invention, it will be apparent that details thereof may be varied without departing from the teachings thereof. For example, while I have illustrated my invention in connection with a tetrode, it is obvious that it is equally applicable to a pentode or to the other multielement tubes. Furthermore, while I have shown a birdcage type of electrode assembly, it will be apparent that other forms of assembly may be used embodying my invention.

Accordingly, while I have described above the principles of my invention in connection with specific apparatus, it is to be clearly understood that this description is made only by way of example and not as a limitation on the scope of my invention as set forth in the objects of my invention and the accompanying claims.

I claim:

20. 1. A beam type electron discharge device comprising an anode, a cathode and at least one control element, said element being mounted relative to and providing a clear path between said anode and cathode, said cathode being comprised of a filamentary element having a segmental cross section and having electrically emissive and non-emissive surfaces, said emissive surfaces being flat and facing along the path and all of said non-emissive surfaces being away from said anode.

25. 2. A beam type electron discharge device comprising an anode, a cathode, at least one grid having a plurality of elements mounted between said anode and cathode, said elements of the grid providing at least one clear path between said anode and cathode, said cathode comprising spaced parallel filamentary elements lying equidistant from said anode, there being one of said filamentary elements for each path, said cathode elements having electronically emissive surfaces and surfaces coated with substantially non-emissive material, the emissive surfaces of said cathode elements facing toward the anode with all of the non-emissive surfaces of said cathode facing away from said anode.

30. 3. A beam type electron discharge device according to claim 2, in which the cathode is of the thoriated tungsten type whose emissive surface is carburized and whose non-emissive surface is uncarburized.

35. 4. A beam type electron discharge device according to claim 2, wherein the emissive surface of said cathode is flat and the non-emissive surface is curved.

40. 5. A beam type electron discharge device according to claim 2 wherein the non-emissive surface of said cathode is covered with a coating of an emission inhibiting material.

45. 6. A beam type electron discharge device comprising an anode, a cathode, and a plurality of grids mounted between said anode and cathode, each of said grids including a plurality of grid elements equally spaced, the corresponding elements of each of said grids being aligned and providing clear paths between the anode and cathode, said cathode comprising spaced parallel filamentary elements lying equidistant from said anode, there being one of said cathode elements for each path, said cathode elements having electronically emissive surfaces and surfaces coated with substantially non-emissive material, the emissive surfaces of said cathode elements facing toward the anode along said paths, with all of the non-emissive surfaces of said cathode facing away from said anode.

7. A beam type electron discharge device according to claim 6 wherein said electronically emissive surfaces are flat and said substantially non-emissive surfaces are curved.
